United States Patent Office

Des. 215,968
Patented Nov. 11, 1969

215,968

STEREOPLOTTER

John F. Henshaw, San Francisco, and Victor H. Henshaw,
Alamo, Calif., assignors to Keuffel & Esser Company,
Hoboken, N.J., a corporation of New Jersey

Filed June 18, 1968, Ser. No. 12,422

Term of patent 14 years

Int. Cl. D16—08

U.S. Cl. D57—7

FIG. 2

FIG. 3

FIG. 1 is a perspective view taken from the front and left side of a stereoplotter embodying our new design;

FIG. 2 is a rear elevational view thereof; and

FIG. 3 is an elevational view taken from the right side thereof.

The broken line representation of the projectors and projector supporting beam in FIG. 1 is for the purpose of illustration only.

We claim:

The ornamental design for a stereoplotter, as shown and described.
